DESIGN FOR A SIGNAL DEVICE

Morris A. Lipschultz, Chicago, Ill.

Application March 25, 1940, Serial No. 91,231

Term of patent 7 years

To all whom it may concern:

Be it known that I, Morris A. Lipschultz, a citizen of the United States, residing at Chicago, county of Cook, and State of Illinois, have invented a new, original, and ornamental Design for a Signal Device, of which the following is a specification, reference being had to the accompanying drawing forming a part thereof, in which:

Figure 1 is a front elevational view of a signal device showing my new design;

Figure 2 is a side elevational view of the same; and

Figure 3 is a plan view thereof.

I claim:

The ornamental design for a signal device, as shown.

MORRIS A. LIPSCHULTZ.
